UNITED STATES PATENT OFFICE.

FREDRED G. GURLEY, OF NEWPORT, KENTUCKY.

COMBINATION TOOL.

Application filed August 4, 1923. Serial No. 655,631.

To all whom it may concern:

Be it known that I, FREDRED G. GURLEY, a citizen of the United States, residing at Newport, in the county of Campbell and State of Kentucky, have invented new and useful Improvements in Combination Tools, of which the following is a specification.

This invention relates to improvements in tools, and has for an object the provision of 10 a combination saw, square, level, plumb, and rule, and providing a convenient and useful tool for the use of carpenters and others.

Another object of the invention is the provision of a square which includes novel 15 means for mounting one of the blades, so that the blade will be out of the way when the tool is used as a saw, may be conveniently moved out of and into position, and when in use will be yieldingly held in place.

20 With the above and other objects in view, the invention further includes the following novel features and details of construction to be hereinafter more fully described, illustrated in the accompanying drawings, and 25 pointed out in the appended claims.

In the drawings:—

Figure 1 is an elevation of the tool with the short blade of the square shown extended by dotted lines,

30 Fig. 2 is a top edge view,

Fig. 3 is a section on the line 3—3 of Fig. 1,

Fig. 4 is a detail perspective view of the short blade, and

35 Fig. 5 is a similar view of the block.

Referring to the drawings in detail wherein like characters of reference denote corresponding parts, the reference character 10 indicates the blade of a saw to which is secured a handle or grip 11.

40 This handle or grip is notched at its front edge and on each side of the blade as at 12 and located within this notch is a plumb level 13, the spirit of which is visible through opening 14.

The handle or grip is further provided with a plumb level 16 and the spirit of this level is also visible through an aperture 17 and a notch 18.

50 The back edge of the saw blade 10 is straight as shown at 19 and is graduated as at 20 to provide a rule, the graduations being preferably upon both sides of the blade adjacent the edge 19. This edge is arranged 55 parallel with the level 16 so that the said edge may be placed against a perpendicular

wall or object and the tool used as a plumb, the result being read on the level 13. The level 16 may be used as a plane level when the edge 19 is placed upon a horizontal member. The edge 21 of the saw handle and the edge 19 of the saw blade form a right angle, and by placing these edges against the edge of a board either edge may be used as a plumb or as a square, the levels 60 13 and 16 functioning in the first instance, while the combined edges 19 and 21 may function as a square.

The blade 10 of the saw is secured within a notch 22 provided in the handle 11 and communicating with this notch is a recess 23. Secured within this recess is a block 24 to which is pivotally secured as at 25, one end of a relatively short blade 26. The end of this blade is reduced so as to provide a 75 shoulder 27 which is adapted to abut the adjacent edge of the block 24 and limit the movement of the blade in one direction, in which position the blade will be at a true right angle with respect to the edge 19 of 80 the saw blade. The block 24 is provided with a projection 28 which is adapted to enter and yieldingly engage the walls of a recess or socket 29 provided in the reduced portion of the blade 26 so as to yieldingly 85 hold the blade in extended position. The relative positions of the projection 28 and socket 29 are such that when the blade is extended as shown by the dotted lines in Fig. 1, the projection will enter the socket so as 90 to hold the blade at a true right angle. The blade 26 however may be folded inward within a groove 30 provided in the handle 11, the said groove communicating with the recess 23 which houses the block 24. The 95 blade 26 is also graduated as shown.

The invention is susceptible of various changes in its form, proportions, and minor details of construction and the right is herein reserved to make such changes as properly fall within the scope of the appended claims.

Having described the invention what is claimed is:—

1. The combination with a saw blade having a straight edge and a handle, said handle being provided with a recess adjacent the blade and a groove having one end in communication with the recess, of a pivot block secured within the recess, a relatively short blade reduced at one end and provided with a shoulder and pivotally secured to the block, whereby the said blade may be 105 110 115

swung outward to a right-angular position when the shoulder engages the edge of the block, and means for holding the pivoted blade against inward movement.

5 2. The combination with a saw blade having a straight edge and a handle, said handle being provided with a recess adjacent the blade and a groove having one end in communication with the recess, of a pivot block 10 secured within said recess, a relatively short blade reduced at one end and provided with a shoulder and pivotally secured to the

block, whereby the blade may be swung outward to a right-angular position when the shoulder engages the edge of the block, and means for holding the pivoted blade against inward movement, said means including a projection upon one face of the block and said projection yieldingly engaging the walls of a socket provided in the adjacent face of 20 the blade.

In testimony whereof I affix my signature.

FREDRED G. GURLEY.
